Richard J. Cook

UNITED STATES PATENT OFFICE.

STANLEY B. HOLMES, OF SEATTLE, WASHINGTON.

FUEL-MIXING DEVICE.

Application filed July 27, 1922. Serial No. 577,896.

To all whom it may concern:

Be it known that I, STANLEY B. HOLMES, a citizen of the United States, and a resident of Seattle, county of King, and State of Washington, have invented certain new and useful Improvements in Fuel-Mixing Devices, of which the following is a specification.

This invention relates to improvements 10 in fuel mixing devices for use in connection with internal combustion engines, and has for its principal object to provide means for supplying moisture or moistened air to the explosive mixture as it is delivered 15 through the intake manifold to the engine's cylinders.

A further object of the invention resides in the provision of a device of the above character that may be applied between the 20 carbureter and end of the intake manifold and which has a valve controlled supply tube connection with the radiator of the vehicle through which the moisture is drawn by suction produced by operation of 25 the pistons within the cylinders.

A still further object of the invention resides in the details of construction of the device whereby a Venturi tube effect is accomplished which causes a better mixing 30 of the moisture and fuel gases than has heretofore been possible.

In accomplishing these and other objects of the invention, I have provided the improved details of construction, the preferred 35 forms of which are illustrated in the accompanying drawings, wherein—

Figure 1 is a side view of an internal combustion engine equipped with a fuel mixing attachment constructed and applied 40 according to the present invention.

Figure 2 is an enlarged, sectional view through the device and the adjacent parts of the carbureter and fuel inlet manifold between which it is applied.

Figure 3 is a sectional view taken on the line 3—3 in Figure 2.

Figure 4 is a horizontal section taken on the line 4—4 in Figure 2; a part of the mixing device being broken away for better 50 illustration.

Referring more in detail to the several views of the drawings, wherein like reference numerals designate the same or like parts—

1 designates what may be an internal combustion engine of any of the ordinary

types of construction used in motor driven vehicles, and 2 designates an inlet manifold whereby fuel vapor is delivered from a carbureter 3 to the several cylinders of the 60 engine. The manifold has an end flange 4 and the carbureter has a corresponding flange 5 between which a fuel mixing device, designated as a whole at 6, in Figure 1, is secured by means of bolts 7 extended 65 through the ends of the same and the flanges 4 and 5.

The fuel mixing device consists of a metallic block 8 provided with a central opening 9 wherein a ring 10 is tightly fitted. 70 This ring has an annular interior channel 11 provided at one side, as shown in Figure 4, with an opening 12 which registers with a bore 13 leading from one side of the block and into which a valve 75 casing 14 is threaded. The casing is connected by means of a small tube 15 with the top of the engine's radiator 16 wherein water is maintained for cooling purposes and which, at most times, is steaming or 80 in a heated condition. The casing is equipped with a rotatable valve whereby the amount of flow of water is controlled and this has connected thereto a rod 17 which may extend to a place where it is 85 readily accessible to the driver of the vehicle.

The opening through the ring 10 is of lesser diameter than the interior of the manifold and this is accomplished by sloping the walls, from the upper and lower edges, inwardly, giving the ring a Venturi tube effect as is clearly shown in Figures 2 and 3. In the upwardly facing wall, and located close to the opening, are upwardly directed apertures 20 through which the water, steam, or moistened air may be drawn by suction created within the manifold.

With the fuel mixing device so constructed and assembled with the parts of the engine, as is illustrated, and with the fuel supply tube connected with the upper portion of the radiator of the engine, it is readily apparent that, upon operation of 105 the engine, there will be vacuum pressure created within the inlet manifold which will cause the carbureted fuel to be drawn into the manifold from the carbureter. Also, this suction will cause the vapor to be 110 drawn into the manifold through the apertures provided in the ring 10 and this vapor

will be readily mixed with the fuel gases as it passes into the manifold.

In instances when the engine has not been running a sufficient time to heat up the water within the radiator, the ring 10 will be filled with water and this will be drawn into the manifold in the form of vapor. After the engine has been running a sufficient length of time to heat the radiator, steam will be produced which will be taken into the manifold in this form. In some instances, only moistened air may be intaken.

It is further apparent that the Venturi tube effect produced by the ring will cause a compression of the fuel vapor as it passes through the opening and then a rapid expansion. This causes a downward swirling, as is illustrated by the arrows in Figure 3, just above the ring which causes a re-mixing of the fuel vapor and the mois-

ture and thereby a better mixture is produced than otherwise is possible.

Having thus described my invention, what I claim as new therein and desire to secure by Letters-Patent, is:

A fuel mixing device adapted to be interposed in the piping between a carburetor and point of combustion of an internal combustion engine comprising a casing having a Venturi passage therethrough and an annular channel about the passage, means for conducting air and water vapor into the said channel and a plurality of small openings in the casing leading from the channel and opening upwardly into the Venturi passage beyond its most restricted part and in the direction of flow of the fuel through the device.

Signed at Seattle, Washington this 21st day of July 1922.

STANLEY B. HOLMES.
